TOOL

Alan E. Brickman, Monongahela, Pa., assignor to
The American Steel and Wire Company of New
Jersey, a corporation of New Jersey

Application July 18, 1942, Serial No. 451,479

3 Claims. (Cl. 81—5.1)

This invention is a tool for use in connection with the installation of the safety reflector assembly disclosed and claimed by Patent 2,274,661, the present application being a continuation of an application filed January 15, 1940, and bearing Serial No. 313,955.

A specific example of the tool is illustrated by the accompanying drawing, the various figures being as follows:

Figure 1 is a side view;

Figure 2 is a view showing the side at the top in Figure 1;

Figure 3 is a longitudinal section of the tool in action;

Figure 4 shows an element of the tool removed for better study; and

Figure 5 is a cross-section from the line V—V in Figure 4.

More specifically, these drawings show the lens receptacle 2 inserted in its hole in the bracket 7 with its flange 3 flush against the outside surface of the bracket, the receptacle being anchored in this hole by projections 8 punched out from the receptacle side wall and engaging the back side of the bracket 7, all as shown in the enumerated patent. The illustrated tool is particularly designed to conveniently cut and punch out the projections 8 so that they will properly anchor the receptacle 2 tightly in place in as vandal-proof a manner as possible, and so that they will not permit undue water seepage between their lips and the back of the bracket 7.

This tool has a frame 10 from which projects a longitudinally slotted stud 11 insertable through the open end of the receptacle or shell 2. Preferably the frame 10 and stud 11 are made of solid integral metal, the slot 12 in the stud 11 cutting transversely entirely through the stud and going back into the frame 10 and then diverging to leave a solid integral frame part 13 which is sufficiently sturdy and massive to effectively maintain the frame and stud as an integral unit. Lever arms 14 oppositely swing radially of the stud 11 in its slot 12 about pivots 15 on the frame 10 that are axially transversely aligned with the stud side. Each lever arm 14 is provided with a longer handle arm 16 that extends backwardly from the frame 10, so that when the handle arms are squeezed together manually the lever arms 14 oppositely swing apart, a compression coil spring 17 carried in a bore 18 formed transversely through the solid frame-joining part 13, serving to keep the handles 16 spring-urged apart to an extent determined by abutments 19 formed on the insides of the lever arms 14 and which engage a

pin 20 extending transversely through the slot within which the arms 14 swing.

Each of the swinging ends of the arms 14 carries a punch projecting outwardly respecting the stud slot with a flat base 21 transverse of the arm tangent an arc about the pivot axis of the pivot 15, and with an outside 22 that tapers from the base 21 toward the arm end, the outwardly tapering outside 22 forming a sharp cornered junction 23 with the base 21, which works as a cutting edge for the metal shell wall. Each of the arms 14 is shaped between the punch base 21 and the arm pivot 15 throughout the slot length within the stud 11, to remain at least flush with the stud side when the arm is swung outwardly respecting the stud slot to cause the punch to project to shell side wall punching position beyond the stud wall. Preferably, this portion of the arm just described, should be shaped to be truly flush with the stud side when the arm is swung outwardly of the stud slot to cause the stud to project to shell side wall punching position beyond the stud side, the latter and this arm portion outside, indicated at 24, being shaped to fit the shell side wall inside contour, or, in the illustrated instance, to constitute a smooth cylinder of just slightly less diameter than the cylindrical shell lens receptacle, when the punch fully projects beyond the stud side. The punch outside 22 is shaped as a cone sector, but other equivalent shapes may also be used.

Reference to Figure 4 shows one of the arms 14 with its extending handle arm 16, removed from the frame for better study, it being understood that the arms 14 and 16 are preferably integral parts of sufficient sturdiness. In this figure, the transverse pivot axis is shown at A aligned with the stud side indicated by the dotted line B, and with the flat base 21 of the punch tangent an arc C about the axis A, the plane of the base 21 being indicated by the dotted line D. The portion 24 of the arm 14 is shown in line with the axis A and the line B. These features are important.

In use, the shell 2 may be slipped over the stud 11 and the tool used to place the shell in its hole in the bracket 7 so as to bring its flange 3 flush with the outside of this bracket, it being understood that the abutments 19 and the pin 20 are arranged so that the spring 17 forces the handles 16 apart to a degree completely retracting the punches on the ends of the arms 14, within the slot 12. The handle arms 16 are then squeezed together, this causing the sharp corners 23 of the punches to start to cut the shell closely ad-

jacent the back side of the bracket 7, the frame 10 providing a shoulder 25 at the stud base which limits the stud's insertion in the shell and, in conjunction with proper design of the arms 14, bringing the punches to proper positions to start the cuts as described. Due to the axes of the pivots 15 being in line with the stud sides, the punch motions are substantially linear, they moving diametrically oppositely from the stud in directions substantially parallel the line D until their flat bases are mutually exactly parallel by coming to right angular relation with the stud side or line B, the arcs through which they work being short. As the punches continue to move outwardly, their conical sector surfaces 22 draw 15 the metal side wall of the shell 2 into corresponding conical sectors while cutting the bases of these sectors so that they can leave the shell side wall plane, this action continuing until the portions 24 of the two lever arms 14 engage the shell 20 inside and stop the action. Since these portions 24 coincide with the inside shell contour, the shell cannot be unduly stressed out of shape should the hole in the bracket 7 be somewhat too large. The result is the projections 8 shown 25 in the patent, and which safely anchor the shell 2 against the removal except by means of a special tool. The lips of the conical sector projections 8 fit tightly against the back side of the bracket 7 due to the substantially linear action 30 of the punches and due to the fact that when these punches attain full operating positions, their bases 21 each become normal the line B defining the stud side and the pivot axis C aligned therewith, the very slight departures 35 from a linear direction involved by the punches, being in a direction tending to draw the projections 8 toward the back side of the bracket 7, whereby the lips of these projections bounding 40 their bases are in substantial engagement with the bracket back side, this reducing water seepage to a minimum.

There are a large number of tools of the general character of the one herein disclosed, that have been known to the prior art for a considerable time, but all of these have involved actions capable only of bending out shell portions in such a manner that it is relatively easy to bend back the portions and remove the shell. None of them have permitted an approach to a linear punch action excepting those involving complicated reciprocating cam actions involving much greater manufacturing costs and such a loss of simplicity as to render them unreliable for field use. The conical sectors punched out by the present tool cannot be displaced by punching and prying unless so much force is used as to tear them completely from the shell walls. It is usually desirable to make four of the projections 8, this being done by releasing the handle arm 16, giving the tool a turn, and again operating it. It is for this reason that the tool is shown as provided with two punches and operating levers, it being possible for the tool to operate in the same manner as described when only one punch is used, this being due to its peculiar design providing for a punch that operates in a substantially linear fashion to cut and draw the projection as described, as contrasted to bending or tearing out portions of the shell by an eccentric swinging punch operating more like a bending or pulling hook.

I claim:

1. A tool for punching out a projection from the side wall of an open-ended shell and which includes a frame from which projects a longitudinally slotted stud insertable through the shell open end, said stud being substantially the same size as the opening, said frame having a lever arm swinging radially of the stud in its slot, a pivot for said lever arm mounted on the frame, the axis of said pivot being transverse, aligned and substantially tangent thereto, and the stud side with the swinging arm end having a punch projecting outwardly respecting the stud slot with a flat base transverse of the arm tangent to an arc about the pivot axis and an outside that tapers from the base toward the arm end and which forms a sharp cornered junction with the base, the arm being shaped between the punch base and the arm pivot throughout the slot length to remain at least flush with the stud side when the arm is swung outwardly respecting the stud slot to cause the punch to project to shell side wall punching position beyond the stud side.

2. A tool for punching out a projection from the side wall of an open-ended shell and which includes a frame from which projects a longitudinally slotted stud insertable through the shell open end, said stud being substantially the same size as the opening, said frame having a lever arm swinging radially of the stud in its slot, a pivot for said lever arm mounted on the frame, the axis of said pivot being transverse, aligned and substantially tangent thereto, and the stud side with the swinging arm end having a punch projecting outwardly respecting the stud slot with a flat base transverse of the arm tangent to an arc about the pivot axis and an outside that tapers from the base toward the arm end and which forms a sharp cornered junction with the base, the arm being shaped between the punch base and the arm pivot throughout the slot length to remain at least flush with the stud side when the arm is swung outwardly respecting the stud slot to cause the punch to project to shell side wall punching position beyond the stud side, the latter and the arm outside being shaped to fit the shell side wall inside contour.

3. A tool for punching out a projection from the side wall of an open-ended shell and which includes a frame from which projects a longitudinally slotted stud insertable through the shell open end, said stud being substantially the same size as the opening, said frame having a lever arm swinging radially of the stud in its slot, a pivot for said lever arm mounted on the frame, the axis of said pivot being transverse, aligned and substantially tangent thereto, and the stud side with the swinging arm end having a punch projecting outwardly respecting the stud slot with a flat base transverse of the arm tangent to an arc about the pivot axis and an outside that tapers from the base toward the arm end and which forms a sharp cornered junction with the base, the arm being shaped between the punch base and the arm pivot throughout the slot length to remain at least flush with the stud side when the arm is swung outwardly respecting the stud slot to cause the punch to project to shell side wall punching position beyond the stud side, the punch outside being at least approximately a cone sector.

ALAN E. BRICKMAN.
